United States Patent Office

Des. 224,687
Patented Aug. 29, 1972

224,687

WEBBED HORSESHOE

Norman C. Jeckel, P.O. Box 22, Steamboat
Springs, Colo. 80477

Filed Feb. 11, 1971, Ser. No. 114,748

Term of patent 14 years

Int. Cl. D30—99

U.S. Cl. D30—35

FIG. 3

FIG. 1

FIG. 4

FIG. 2

FIG. 5

FIG. 1 is a top plan view of a webbed horseshoe, showing my new design;

FIG. 2 is a bottom plan view;

FIG. 3 is a front elevational view;

FIG. 4 is a rear elevational view;

FIG. 5 is a left side elevational view, the right side being substantially a mirror image thereof.

I claim:

The ornamental design for a webbed horseshoe, as shown and described.
